HASSOCK AND METHOD OF MANUFACTURING THE SAME

Anthony Wilson, Beaver County, Pa.

Application April 26, 1950, Serial No. 158,095

12 Claims. (Cl. 155—169)

1

This invention relates to a hassock and to a method of manufacturing hassocks.

Conventional forms of hassock construction do not satisfactorily combine lightness, strength and ease of manufacture, and it is difficult to fasten the edges of upholstery to conventional hassock frames in a neat and secure manner.

The hassock of my invention is light and strong and the upholstery is firmly secured in place. I form the frame by constructing a series of separate structural units, assembling the units in adjacent stacks, placing the stacks between common top and bottom cover members, and bolting the cover members together through the stacks of units. Since each unit may be identical with other units of the same stack, and since the components of various units in all of the stacks may be identical, it is possible in accordance with my invention to construct a strong hassock quickly and inexpensively. Moreover, the respective units are preferably covered along their exposed portions with individual pieces of upholstery before the hassock is assembled, with the edges of the pieces of upholstery secured between units or between the units and cover members so that the upholstery edges are neatly concealed and are firmly held and protected when the whole assembly is completed. This method and form of construction is particularly suitable for heart-shaped hassocks and the like which have grooves therein which are difficult to upholster in accordance with conventional practices.

Other details, objects and advantages of the invention will become apparent from the following detailed description and in the accompanying drawing. I have shown in the drawing, for purposes of illustration only, the following present preferred embodiment of my invention in which

Figure 1 is a plan view of the upholstered frame of a component unit for a hassock embodying my invention;

Figure 2 is a side view of the unit shown in Figure 1;

Figure 3 is a partially sectioned front view of a completed hassock;

Figure 4 is a section on the line IV—IV of Figure 3;

Figure 5 is a detailed partial enlargement of the upper central portion of Figure 4;

Figure 6 is a detailed partial enlargement of the top right portion of Figure 3; and

Figure 7 is a detailed partial enlargement of the juncture of the two upper units at the right of Figure 3.

2

Referring now more particularly to the drawing, the illustrated hassock 10 is heart-shaped and comprises six identical separate component units 11, 12, 13, 14, 15 and 16 each in the shape of a half of a heart. The units 11, 12 and 13 are arranged in a vertical stack shown to the left of Figure 3 and the units 14, 15 and 16 are arranged in a vertical stack shown to the right of Figure 3. The framework of the unit 14, for example, is illustrated in Figures 1 and 2 and comprises a flat plywood top cover piece 17, a flat plywood bottom piece 18, a curved plywood side piece 19 and a series of vertical blocks 20 secured to the inner side of the side piece 19. The top and bottom pieces 17 and 18 each have three openings 21, 22 and 23 to receive three vertical tie rods for holding the stack of units 14, 15 and 16 together. It will be observed that the two stacks of units represent symmetrical halves of the complete hassock and any unit in one of the stacks may be substituted for any unit in the same stack or may be turned upside down and substituted for any unit in the adjacent stack.

When the framework of a unit is completed a generally rectangular strip of upholstery is placed around the exposed side of the unit with any desired padding therebetween, and the edges of the upholstery are tacked onto the top and bottom cover pieces of the unit and to the vertical blocks 20 at opposite ends of the unit. For example, as shown in Figures 3 and 4, a rectangular piece of upholstery material 24 is placed around the outside of the side piece 19 of the unit 14 with padding material 25 therebetween. The upper edge of the material 24 is tacked to the top cover piece 17 of the unit 14, the lower edge is tacked to the bottom cover piece 18 of the unit 14, and the respective vertical edges of the material 24 are tacked to vertical blocks 26 and 27 secured to the ends of the side piece 19. A similar piece of upholstery material 28 is tacked in the same way to the adjacent lower unit 15. When the two units are brought together the lower edge of the material 24 and the upper edge of the material 28 are clamped therebetween. The vertical edges of the material 24 are similarly clamped between the blocks 26 and 27 of the unit 14 and the corresponding blocks 26a and 27a of the unit 11 when the units 11 and 14 are brought together during assembly of the hassock.

After the individual units have been constructed and have been individually upholstered the units are assembled in two adjacent stacks as illustrated in Figures 3 and 4, with the edges of the upholstery clamped between adjacent units as described above. Decorative welts 29 and 30

may be placed around the assembled units along the horizontal lines of juncture of the stacked units. An integral strip along each welt is preferably tacked to adjacent lower units and then is clamped between the stacked units so that the welt is held securely in place (Figures 3 and 7). A heavy top cover member 31 is placed across the top of the complete assembly of units and a like heavy bottom cover member 32 is placed across the bottom of the complete assembly of units (Figure 3). The members 31 and 32 are bored and countersunk at six places 33 corresponding to the openings through the individual units such as the openings 21, 22 and 23 of the unit 14 shown in Figure 1, and six tie rods 34 are inserted through these openings in the cover members 31 and 32 and units 11-16 and are bolted to the members 31 and 32 in order to form a strong unitary structure. It will be observed that the cover members 31 and 32 are bolted together by the tie rods 34 so that the units are securely drawn together vertically, and the tie rods 34 through the top and bottom cover pieces of each unit securely hold the units together against horizontal displacement. The vertical blocks secured to the side pieces of the units, such as the blocks 20 illustrated in Figures 1 and 2, are in line with each other in each stack of units and support vertical compression forces on the completed hassock.

The upper edges of the pieces of upholstery around the upper units 11 and 14 and the lower edges of the pieces of upholstery around the lower units 13 and 16 are clamped between these units and the members 31 and 32 respectively so that all of the edges of the pieces of upholstery around the various units are tucked out of sight and are clamped securely between adjacent units or between the units and the top and bottom cover members. Suitable padding 35 and upholstery 36 is secured to the top cover member 31 to provide a comfortable seat and to cover the upper ends of the tie rods 34, and metal gliders 37 are secured to the bottom of the bottom cover member 32 for convenience in moving the hassock across a floor.

The preferred method of assembly comprises constructing and separately upholstering the units 11-16, mounting the tie rods 34 to project upwardly from the bottom cover member 32, fitting the pre-upholstered lower units 13 and 16 over the rods 34 and dropping them down onto the cover member 32, tacking the welt 30 around the upper edges of the units 13 and 14, dropping the next pre-upholstered units 12 and 15 into place along the rods 34 and similarly tacking the welt 29 around their upper edges, adding the top pre-upholstered units 11 and 12, and the top cover member 31, and bolting the tie rods 34 to the top cover member 31 and then upholstering the cover member 31 to conceal and cushion the upper ends of the tie rods 34. In this way the tie rods 34 aid in aligning the units and speed the assembly.

While I have illustrated and described a present preferred embodiment and method of practicing the invention, it will be recognized that the invention is not limited thereto but may be otherwise variously practiced within the scope of the appended claims.

I claim:

1. A hassock or the like comprising a plurality of separate structural units assembled in a plurality of side-by-side stacks, a pair of cover members extending across opposite ends of said stacks, and tie members fastened to said cover

members and extending through the units in said stacks, whereby the units are held together by said tie members and cover members to form a unitary frame.

5 2. A hassock or the like comprising a plurality of separate and substantially identical structural units assembled in a plurality of equal side-by-side stacks, a pair of cover members extending across opposite ends of said stacks, and tie rods fastened to said cover members and extending through the units in said stacks, whereby the identical units are held together by said tie rods and cover members to form a unitary frame.

10 3. A hassock or the like according to claim 2 wherein each of the identical units comprises a plurality of spaced blocks extending from the top to the bottom of the units, whereby said blocks support vertical compressive loads on the stacked units.

15 20 4. A hassock or the like comprising a plurality of separate structural units assembled in a plurality of side-by-side stacks, a pair of cover members extending across opposite ends of said stacks, pieces of upholstery extending over exposed portions of said units with some edges of said upholstery pieces tucked between adjacent units and other edges thereof tucked between adjacent cover members and units, and means extending through the units in said stacks and the cover members to clamp the assembly together with the said upholstery edges securely disposed within the assembled hassock or the like.

25 35 5. A hassock or the like comprising a plurality of separate structural units assembled in a plurality of equal side-by-side stacks, a pair of cover members extending across opposite ends of said stacks, separate pieces of upholstery extending over exposed portions of units with some edges of said upholstery pieces tucked between adjacent units and other edges of some of the upholstery pieces tucked between adjacent cover members and units, and tie rods extending through the units in said stacks and fastened at either end to the cover members to clamp the assembly together with the said upholstery edges securely disposed within the assembled hassock or the like.

30 40 6. A hassock or the like according to claim 5 wherein the units are substantially identical and the stacks are equal.

45 7. A hassock according to claim 6 wherein the hassock is heart-shaped and the units are each in the shape of half of a heart divided symmetrically.

50 55 8. A hassock according to claim 7 wherein the cover members are each heart-shaped and comprising upholstery and cushioning means secured over one cover member to conceal and cushion the ends of the tie rods fastened thereto.

60 65 9. A method of constructing a hassock comprising stacking a plurality of separate structural units one on top of another in a plurality of separate stacks, bringing the stacks together side-by-side and placing a top cover piece across the top and a bottom cover piece across the bottom of the side-by-side stacks, extending tie members through each stack, and securing said members to the top and bottom cover pieces, thereby forming a unitary hassock frame.

70 75 10. A method of constructing a hassock comprising the steps of applying pieces of upholstery material to separate structural units, with edges of said pieces of material extending to portions of said units which are not exposed when the

units are assembled into a completed hassock, stacking the units in separate stacks and bringing the stacks together with said edges of upholstery material between adjacent units, and fastening the units together.

11. A method of constructing a hassock comprising the steps of applying pieces of upholstery material to separate structural units, with edges of said pieces of material extending to portions of said units which are not exposed when the units are assembled into a completed hassock, stacking the units in separate stacks and bringing the stacks together with edges of said pieces of upholstery material tucked between adjacent units, placing a top cover member across the top and a bottom cover member across the bottom of the side-by-side stacks with edges of said pieces of upholstery material on the top and bottom units tucked between said cover members and adjacent units, and fastening the cover members tightly together with the units therebetween and the said upholstery edges securely tucked within the completed structure.

12. A method of constructing a hassock comprising the steps of applying pieces of upholstery material to separate structural units, with edges of said pieces of material extending to portions of said units which are not exposed when the

units are assembled into a completed hassock, stacking the units in separate stacks and bringing the stacks together with edges of said pieces of upholstery material tucked between adjacent units, placing a top cover member across the top and a bottom cover member across the bottom of the side-by-side stacks with edges of said pieces of upholstery material on the top and bottom units tucked between said cover members and adjacent units, and extending tie members through each stack and securing said members to the top and bottom cover pieces, thereby forming a unitary hassock frame with the upholstery edges securely tucked within the completed structure.
